CLAIM

The ornamental design for a double-sided top water lure body, as shown and described.

DESCRIPTION

FIG. 1 is a top front perspective view of a double-sided top water lure body, showing my new design;

FIG. 2 is a bottom front perspective view thereof;

FIG. 3 is a front elevation view thereof, with the rear elevation view being a mirror image thereof;

FIG. 4 is a right side elevation view thereof;

FIG. 5 is a left side elevation view thereof; and,

FIG. 6 is a top plan view thereof, with the bottom plan view being a mirror image thereof.

The broken lines shown in the drawings depict portions of the article that form no part of the claimed design.
